UNITED STATES PATENT OFFICE.

JOHN T. McGARRY, OF CINCINNATI, OHIO.

RAILWAY WATER COLUMN.

Application filed October 25, 1924, Serial No. 745,786. Renewed November 30, 1928.

My invention relates to railway water columns wherein a revoluble standpipe is employed having a nozzle extending laterally outward from the upper portion thereof and 5 provided with a discharge spout whose rear end envelopes and is adapted to telescope over the nozzle. It is an object of my invention to provide a discharge nozzle of such form and extent relative to the spout, and a 10 mounting for the rear end of the spout, which will permit movement of the rear end of the spout longitudinally of the nozzle in both directions from its neutral or hanging position, thereby giving extensive adjustment 15 range of the discharge end of the spout both horizontally toward and from the standpipe and vertically in the plane of the standpipe, and at the same time giving sufficient clearance 20 for coal piles, car ends and any other obstruction which might be adjacent the tender manhole. In accomplishing these objects the spout is of such length and so supported upon the standpipe that in inoperative position its lower margin will lie substantially 25 horizontal and the spout end may extend materially beyond the plane of the water opening. This form of suspension, together with the enlarged rear opening of the spout, makes it possible to swing the spout back upon the 30 nozzle in adjusting the same to the higher tank openings, and permits the spout to swing along the elongated nozzle to enter the openings of intermediate and very low tenders, thus giving an extraordinary range of delivery 35 to the end of the spout, and at the same time carrying it at the highest possible position for swinging over coal piles and high tender tanks.

The full objects and advantages of my 40 invention will appear in connection with the detailed description thereof and the novel features embodied in my inventive idea will be particularly pointed out in the claims.

In the accompanying drawings which illustrate some of the forms in which my invention 45 may be embodied;

Fig. 1 is a side elevational view of a water column showing a small portion broken away and showing the discharge spout in 50 raised position. Fig. 2 is a top plan view. Fig. 3 is a view in vertical section on the line 3—3 of Fig. 1. Fig. 4 is a view similar to Fig. 1, but showing the spout supported in a slightly different manner. Fig. 5 is a view in 55 vertical section on the line 5—5 of Fig. 4. Fig. 6 is a view in horizontal section on the

line 6—6 of Fig. 4. Fig. 7 is a side elevational view of the construction shown in Fig. 4 and illustrating by dotted lines different positions which the spout may assume. Fig. 8 is a side 60 elevational view showing another manner in which the spout may be supported.

Referring to the construction shown in the drawings, the numeral 10 designates a vertical tubular column which, toward its lower 65 end is provided with a pair of diametrically opposite rollers 12 resting upon a trackway 14 formed at the upper end of a pedestal 18 as shown in Fig. 4. A hood 16 secured to the column extends down outside of the rollers 70 and the trackway to protect them from snow and dirt. The trackway 14 is provided with diametrically opposite notches into which the rollers 12 drop when the column 10 is in such position that a spout 20 carried at the 75 upper end thereof is parallel with railway tracks adjacent which the column is placed. When the column is turned to bring the spout 20 crosswise of the railway tracks, the rollers 12 rise out of the notches in the track- 80 way 14 and the column is lifted. The spout 20 has a hook 22 intermediately secured to the upper side thereof. A spout cable 24 is secured to this hook and the cable which is in two parts passes over a double sheave 26 85 shown in Fig. 3 secured to an I-beam 28 extending out horizontally from the upper end of the column 10. The two branches of the cable pass respectively over two sheaves 30 secured to opposite sides of the column 10 and 90 the lower ends of the cable are secured to a spout weight 32 which is in the form of a ring slidably surrounding the column. This weight balances the spout for ease of operation. A hand loop 34 is secured to the outer 95 end of the beam 28 for use in pulling the spout over the railway tracks on each side of the column. A handle 36 is secured to the outer end of the spout for use in moving it up and down. An operating lever 38 is pivotally 100 attached at 40 to lugs 42 extending up from the column 10. The inner end of the lever 38 is pivotally attached to two rods 44 and 46 which at their lower ends are connected to a valve device which constitutes no part 105 of the invention disclosed in this application. In the form of invention disclosed, in Figs. 1 to 7 inclusive, a housing 48 is secured upon the upper side of the beam 28 so as to enclose a portion of the beam as a trackway for 110 a spool-like roller 50 as shown in Fig. 5 which is held down on the track by a rod 51 secured

to the housing. In the form shown in Figs. 1 to 3, the spindle of this roller at both ends is connected by bars 52 with the inner end of the spout 20 at opposite sides thereof. The form shown in Figs. 4 and 7 is the same as that already described except that the bars 52 are partly replaced by chains 54 which construction renders the spout support still more flexible. The inner end of the spout 10 telescopes loosely over a nozzle 56 extending out laterally from the upper portion of the column, with the outer end of the nozzle curved downwardly. In the form shown in Fig. 8, the inner end of the nozzle 20 is supported by two bell crank arms, each of which consists of an upper member 58 and a lower member 60. The member 58 is pivotally attached at its upper end to the beam 28 while the member 60 is curved in such manner 20 that an upwardly convexed slot 62 extends for substantially the length thereof. The slots 62 receive pins 64 extending out from the sides of the spout 20 at its inner end.

The operation and advantages of my invention will now be obvious. The spout 20, when not in use, is held up in the position shown in Figs. 1 and 4 by the spout weight 32. When a locomotive tender is to be supplied with water, the fireman grasps the loop 30 34 and pulls the spout 20 around so as to extend crosswise of the railway tracks, thus bringing the delivery end of the spout into the plane of the filling opening in the tenders. By pulling downwardly on the spout, it may 35 be made to assume different positions, some of which are indicated by dotted lines in Figs. 7 and 8, wherein the spout is shown as swung back along the nozzle for adjustment to a high tank opening and as being progressively 40 and flexibly swung along the elongated nozzle for adjustment to enter intermediate and very low tank openings. It will be evident that the discharge end of the spout has a wide range of vertical movement and therefore may be inserted in the filling opening of tenders of greatly varying heights. In the 45 operation of the forms shown in Figs. 1 to 7, when the discharge end of the spout is first depressed, the spout may be made to swing inwardly so that its discharge end assumes the position indicated at 20' in Fig. 7. Continued depression of the discharge end of the spout causes the roller 50 to run out on the trackway until the discharge end finally 50 assumes the position indicated at 20''. It will be observed that the center of the discharge end lies in the same vertical line for all positions between 20' and 20''. In the form shown in Fig. 8, when the discharge end of 55 the spout is first depressed, the spout will be made to swing inwardly so that its discharge end assumes a position indicated at 20''. Continued depression of the discharge end causes the pins 64 to slide outwardly in 60 the curved slot 62 until the discharge end 65

finally assumes the position indicated at 20''. It will be observed that the center of the discharge end lies in the same vertical line for all positions between 20'' and 20''. By reference to Fig. 7, it will be apparent that the above described range of movement of the spout is permitted on account of the fact that the inner end of the spout telescopes loosely over the outer end of the nozzle coupled with the further fact that the outer end of the nozzle is downwardly curved. The flexible mounting of the spout also permits it to be swung along the railway tracks to meet the tender instead of having to move the tender to meet the spout. This capability of movement will to a large extent prevent the column from being knocked down by unexpected shifting of the tender.

I claim:

1. In a water column, a revolute standpipe having an outwardly extended delivery nozzle, a spout having an enlarged inner end enveloping said nozzle, a cable and counterweight device supporting the forward end of said spout for front and rear and up and down swinging movements, and flexible means supporting the rear end of said spout, said flexible means being relatively extensible to permit said rear end of the spout to swing along the nozzle.

2. In a water column, a revolute standpipe having an outwardly extended delivery nozzle and an overhanging supporting arm, a spout having an enlarged inner end enveloping said nozzle, a cable and counterweight device supporting the forward end of said spout, and a link connecting said arm and the inner end of said spout and holding said spout for pivotal movement up and down on one end of said link and for swinging pivotal movement in and out from the other end of said link.

3. In a water column, a revolute standpipe having an outwardly extended delivery nozzle and an overhanging supporting arm, a spout having an enlarged inner end enveloping said nozzle, a ring-like counterweight surrounding said standpipe, a cable connecting said counterweight and the forward portion of said spout, and flexible means connecting said arm and the inner end of said spout, said flexible means being relatively extensible to permit said rear end of the spout to swing along the nozzle.

4. In a water column, a revolute standpipe having an outwardly extended delivery nozzle and an overhanging supporting arm, a spout having an enlarged inner end enveloping said nozzle, a ring-like counterweight surrounding said standpipe, a cable connecting said counterweight and the forward portion of said spout and a link connecting said arm and the inner end of said spout and holding said spout for pivotal movement up and down upon one end of said link and for swing-

ing pivotal movement in and out from the other end of said link.

5. In a water column, a revolute stand-pipe having an outwardly extended delivery nozzle, a spout having an enlarged inner end enveloping said nozzle, a rigid member overhanging said spout, a link having a swinging connection at one end with the inner end of the spout and at the other end 10 with the rigid member, and means permitting shifting of the point of swinging connection with the rear end of the spout relative to the point of swinging connection with the rigid member.

15 6. In a water column, a revolute stand-pipe having an outwardly extended delivery nozzle, a spout having an enlarged inner end enveloping said nozzle, a horizontal rigid support extending over said spout, a pair of 20 links pivoted at one set of ends to the rear end of the spout, and a roller on said support adapted to move along the same, said links being pivoted at their other ends to said roller.

25 7. In a water column, a revolute stand-pipe having an outwardly extended delivery nozzle, a spout having an enlarged inner end enveloping said nozzle, a horizontal rigid support extending over said spout, a pair of 30 links pivoted at one set of ends to the rear end of the spout, a roller on said support adapted to move along the same, said links being pivoted at their other ends to said roller, and means on the support limiting the 35 extent of travel of the roller in both directions.

8. In a water column, a revolute stand-pipe having an outwardly extended delivery

nozzle, a spout having an enlarged inner end enveloping said nozzle, a horizontal rigid 40 support extending over said spout, a pair of links pivoted at one set of ends to the rear end of the spout, a roller on said support adapted to move along the same, said links being pivoted at their other ends to said roller, 45 and means on the support limiting the extent of travel of the roller in both directions, said means holding the links so that the rear end of said spout in inoperative position is spaced from the standpipe. 50

9. In a water column, a revolute stand-pipe having an outwardly extended delivery nozzle, a spout having an enlarged inner end enveloping said nozzle, a horizontal rigid support extending over said spout, a pair of 55 flexible members pivoted at one set of ends to the rear end of the spout, and a roller on said support adapted to move along the same, said flexible members being pivoted at their other ends to said roller. 60

10. In a water column, a revolute stand-pipe having an outwardly extended delivery nozzle, a spout having an enlarged inner end enveloping said nozzle, a horizontal rigid support extending over said spout, a pair of 65 links pivoted at one set of ends to the rear end of the spout, a roller on said support adapted to move along the same, said links being pivoted at their other ends to said roller, and spaced lugs on the support on each 70 side of the roller limiting the extent of travel of the roller.

In testimony whereof I hereunto affix my signature.

JOHN T. McGARRY.
